UNITED STATES PATENT OFFICE.

GEORGE C. BLOHM, OF SOUTH BEND, INDIANA.

SHEATHING MATERIAL.

Application filed May 9, 1921. Serial No. 468,020.

To all whom it may concern:

Be it known that I, GEORGE C. BLOHM, a citizen of the United States, residing at South Bend, in the county of St. Joseph and State of Indiana, have invented a new and useful Improvement in Sheathing Materials, of which the following is a specification.

My invention relates, more particularly, to sheathing material for covering the sides and roofs of buildings and which is formed of a foundation of waterproofed felt or any other suitable, preferably flexible, material and which preferably, though not necessarily, is provided with a wear-resisting coating of any desirable form and which is exposed to the elements in the use of the sheathing, this coating being preferably formed of any suitable particles attached to the foundation as is common in prepared roofing.

More particularly stated, my invention relates to prepared sheathing material provided in strips, and more especially to strips each of which presents a body portion from which a plurality of shingle-forming sections, arranged in a series, project, these shingle-strips being so constructed that when assembled together in overlapping relation on a structure to be sheathed, the appearance will be the same as that presented by a structure covered with shingles, as commonly laid.

The laying of sheathing material as hitherto provided, whether in plain strips, strips each presenting shingle sections, or provided as single shingles, presents difficulties desirable to be overcome, the laying of all of the above-referred-to forms of sheathing material requiring considerable care, skill and labor in so placing them as to provide the desirable uniformity of overlap, and the laying of single shingles and shingle strips requiring, in addition, that care be taken to properly and uniformly laterally space the strips and the single strips and the single shingles the required distance apart to produce the desired effect and so position the strips or shingles of adjacent rows that the desired staggered relation of the spaces between shingles or shingle sections of adjacent rows be presented.

My object, generally stated, is to provide strips of sheathing material each preferably presenting along one edge thereof shingle-

forming sections, which may be economically manufactured and quickly laid by relatively unskilled labor, in the proper position on the supporting structure, to present the desired uniform degree of overlap and, where the strips present shingle sections, the desired uniform and accurate staggering of the spaces presented between the shingle sections in each row relative to such spaces provided in adjacent rows of shingle sections. A further, more particular, object is to provide, preferably as an integral part of the shingle-forming strip, the means for the purpose just stated. 70

Referring to the accompanying drawing:

Figure 1 is a plan view of a web of sheathing material from which the strips herein-after referred to may be cut, this view showing the web in the process of being cut 75 into strips embodying my invention. Figure 2 is a plan view of a portion of one of the similar shingle strips embodying my invention. Figure 3 is a plan view of a section of roofing formed of a plurality of the 80 shingle strips shown in Fig. 2; and Figure 4, a broken, perspective view of assembled strips, viewing the structure from the rear, or under, side thereof.

My invention consists in providing a strip 85 of any desirable sheathing material, such, for example, as that above referred to and commonly employed for roofing purposes of any desired length and width, and, preferably, with slots represented at 5 provided 90 therein along one edge thereof, preferably in parallel relation and extending crosswise of the strip at equal distances apart, whereby one edge of the strip, viz., its slotted edge, presents a series of shingle sections 6. In 95 the particular, preferred, illustrated embodiment of my invention, the edge of the strip opposite that containing the slots 5 is notched at intervals as represented at 7 to provide a series of shoulders 8 along this 100 edge of the strip, and the parts of the material which are cut out of the strip to form the notches 7, these parts, being in the form of tongues and represented at 9, being folded backwardly along inclined 105 folding lines 10 to extend crosswise of the length of the strip and in a direction toward the slotted edge thereof, these tongues 9 being preferably secured to lie flatwise against the rear, or under, side of the strip, 110 in any desirable way. Where the rear, or under, side of the strip is sufficiently sticky

as to cause the tongues to adhere thereto, the use of any additional securing means will be rendered unnecessary, but where this is not the case, the tongue 9 may be 5 cemented, or otherwise secured in position as desired.

In producing my improved shingle strip, I may provide the foundation material, treated as desired, to render it waterproof, 10 and then, by any suitable device or mechanism, cut the material into shingle strips of any desired length. In actual practice it probably would be preferred to produce the shingle strips as of relatively great 15 length, by cutting up the web of foundation material, generally in the direction of its length, as for example as shown in Fig. 1 wherein the web represented at 11 is shown as of a width permitting three of 20 the strips to be formed therefrom, though it will be understood that my invention is not limited to the use of any particular material nor to the production of the article by any particular method of manufacture. In the production of the strips as 25 stated and where it is desired that they be cut from the web by machinery, any suitable machine may be employed for this purpose, to cause the shingle sections to 30 present the slots 5, notches 7 and the tongues 9 which latter may be folded to the position shown in the drawings, at any desirable stage in the process of producing the completed strips.

35 In the laying of the shingle strips the strip, or strips, as the case may be, forming the lowermost row of shingle sections, are first laid in position on the supporting structure, and the strip, or strips, to form 40 the next row of shingle strips applied to the supporting structure to overlap the first applied strip, or strips, the tongues 9 of the overlapping strip, or strips, extending into the opposing notches 7 of the first applied strip, or strips, and fitting against the 45 shoulders 8, and the shingle strips for completing the sheathing structure applied to position as just explained of the shingle strips forming the second row of shingles. 50 The tongues 9 are provided of such length as to cause the strips of adjacent rows to overlap the desired distance and their lower edges to be substantially parallel, and the shoulders 8 are so located that the notches 55 5 of adjacent rows of shingle sections will occupy the desired staggered arrangement as shown in Fig. 3, it being preferable, though not necessary, that the notches 7 and tongues 9 be provided of the same 60 number as the slots 5.

65 It will be understood from the foregoing that by constructing sheathing material in accordance with my invention, skilled labor in laying the strips is not necessary, as the various strips become automatically, so to

70 speak, lined up in the proper relation to each other, by the mere act of the operator applying the strips in overlapped relation, with the tongues 9 fitting into the notches 7 as stated, the application of the strips to this position being very easily effected.

75 It will be readily understood from the foregoing that my invention as to a certain feature thereof, is of value whether or not the strips present shingle sections, as the employment thereof, automatically determines the proper overlap of the various rows of sheathing strips; and furthermore, as regards the feature of determining the 80 break-joint relation between the shingle-forming portions of the strips, it is immaterial whether the shingle sections be of the shape shown, or otherwise produced than by the slotting of the edge of the strip as indicated at 5, it being readily understood 85 that the shingle effect may be produced in many other ways, as for example by painting, or otherwise causing the plain edge of the strip to present the appearance of shingle sections. 90

95 While I have illustrated and described a particular construction embodying my invention, and have suggested certain modifications thereof, it will be readily understood that the structure may be otherwise modified and altered without departing from the spirit of my invention, and as an example of a modification the projections on the strips between their edges, and formed by the lower ends of the tongues 100 9 in the particular construction shown, may be provided in any other suitable form and integral, or not, with the strip, as desired. 105

What I claim as new, and desire to secure by Letters Patent, is:

1. A sheathing strip provided with tongues integral with an edge thereof and extending from the upper edge partially across the back of the strip, for positioning said strip relative to an adjacent strip 110 placed beneath it.

2. A sheathing strip provided with tongues integral with an edge thereof and integrally connected with said strip and extending partway across the latter, said edge 115 adjacent said tongues being recessed for positioning it relative to an adjacent strip.

3. A sheathing strip presenting a shingle appearance along one edge, provided with a projection between said edge and the opposite edge of said strip and with a projection at said opposite edge adapted to engage said first-mentioned projection to position said strips longitudinally of each other. 120 125

4. A sheathing strip presenting a shingle appearance along one edge and provided with a tongue extending from the upper edge of said strip and partially across the same at its rear surface, and presenting a 130

projection between said upper edge and the first mentioned edge of said strip, and a projection at said upper edge.

5. A sheathing strip adapted to overlie a second sheathing strip, the first-mentioned sheathing strip having projections on its rear surface and stops on the upper edge of said second strip adapted to engage said means for positioning one strip longitudinally with respect to the other.

6. A sheathing strip presenting a shingle appearance along one edge and provided

with projections on the back of each strip adapted to cooperate with shoulders on the top edge of a similar sheathing strip of 15 shingle appearance when the former is placed over the latter, for causing the portion of the overlapping strip presenting the shingle appearance to occupy a predetermined staggered position relative to the portion of the underlying strip presenting a shingle appearance. 20

GEORGE C. BLOHM.
